UNITED STATES PATENT OFFICE.

HARRY McKEAN CONNER, OF SCRANTON, PENNSYLVANIA.

SELF-LOADING SCRAPER.

1,326,325.

Specification of Letters Patent. Patented Dec. 30, 1919.

Application filed October 19, 1918. Serial No. 258,825.

To all whom it may concern:

Be it known that I, HARRY McKEAN CONNER, a citizen of the United States, residing at Scranton, in the county of Lackawanna 5 and State of Pennsylvania, have invented certain new and useful Improvements in Self-Loading Scrapers, of which the following is a specification.

In mining coal occurring in low seams 10 or in thin and poor quality beds, a scraper has been employed for bringing the coal from the face to the gangway or loading road.

The invention aims to provide a scraper 15 which is self loading and self discharging, loading as it is drawn rearwardly through the loose material and discharging when it reaches the predetermined point in its forward movement for delivery.

20 The invention provides a scraper which opens automatically to receive the load when drawn rearwardly, the material passing into the scraper during its rearward movement, and which automatically closes 25 to retain the load when a pull is exerted to draw the scraper forward and the load confined thereby.

The invention consists of a scraper which 30 is automatic in its action, so far as loading and discharging the load is involved, the opening to receive the load and the closing to confine the load being effected by the tail and pull ropes or cables, respectively.

The drawing illustrates a preferred embodiment of the invention, however, it is to be understood that in adapting the same to meet different conditions, various changes in the form, proportion, and minor details of construction may be resorted to without 35 departing from the nature of the invention as claimed hereinafter.

Referring to the accompanying drawings,

Figure 1 is a top plan view of a scraper embodying the invention.

45 Fig. 2 is a side elevation, the full lines showing the relation of the parts when the scraper is open to receive a load and the dotted lines showing the disposition of the parts when the scraper is closed to confine 50 the load.

Fig. 3 is a front view of the scraper showing the position of the parts when the same is closed.

55 Fig. 4 is a transverse section on the line 4—4 of Fig. 2, looking to the rear showing

the relation of the parts when the scraper is opened.

Corresponding and like parts are referred to in the following description and indicated in the several views of the drawing by like 60 reference characters.

The body of the scraper may be of any construction and relative size and, as illustrated, comprises side walls 1 and a rear closure 2 which is preferably hinged at its 65 lower end about in the plane of the bottom or lower edges of the side walls 1, as indicated. A bracket or casting 3 is secured to the closure or door 2 and a bar 4 is pivotally connected at one end to the bracket 70 3 by means of a fastening 7 and its opposite end is pivoted at 13 to an arm 8 which in turn is pivoted at its lower end to a bracket 9 by means of a fastening 11. The side walls 1 may be connected in any manner and, as illustrated, a plurality of transverse bars are employed, the same being indicated at 10, 19, 20, 21 and 22. While it is preferred to have the body open at its 75 front, top and bottom it is observed that 80 any one or all of the sides may be closed if preferred. Parallel strips 18 are secured at their ends to the transverse bars 19 and 20 and are spaced apart a distance to receive the upper end of the arm 8 and prevent lateral displacement thereof. The bracket 9 is shown attached to the lower 85 transverse bar 10.

The upper or swinging end of the door or closure 2, is beveled to readily penetrate 90 the loose material when the scraper is passing therethrough in its rearward movement. The door 2 may be hinged to the body of the scraper in any manner and, as indicated, brackets 6 are secured to the inner faces of 95 the lower rear corners of the side walls 1 and complementary brackets 5 are attached to the lower corners of the door 2. The brackets 5 and 6 are formed with matching journals and sockets to provide pivot or 100 hinge connections. Within the purview of the invention the door 2 may be hinged in any manner to the body of the scraper so as to swing rearwardly and downwardly into open position and to close by an upward and forward swinging movement.

A tail rope, or cable 15 is connected to the arm 8 in any manner, a link 14 being shown and connected to the arm 8 by the same fastening means 13 pivotally connect- 110

ing the bar 4 to the arm 8. A pull rope, or cable 27 is connected to the arm 8. The ropes or cables 15 and 27 are to be operated in any manner. A pull on the tail rope 15 5 draws the scraper rearwardly and effects an opening and a loading thereof. A pull on the rope or cable 27 effects a closing of the scraper to confine the load and a drawing of the scraper forwardly over the bottom 10 of the mine to deliver the load to the required point of discharge. The arm 8 has a limited movement which is restricted by the transverse bars 19 and 20.

To prevent the rear end of the door 2 digging into the bottom of the passage or drift 15 it is preferred to provide means for holding such rear end slightly elevated, as indicated by the dotted lines *a* in Fig. 2. This is accomplished by means of a stop 25 which is 20 mounted upon the transverse bar 20 and normally held in elevated position by means of a spring 24. The stop 25 is secured to a stem 29 which is mounted in the transverse bar 20 and projects upwardly therefrom and receives a trip 23 at its upper end. 25 When the stop 25 is elevated it engages the upper end of the arm 8 thereby holding the rear end of the door 2 slightly elevated as indicated by the dotted lines *a*. When the stop 25 is depressed the upper end of the arm 8 moves rearwardly a distance to permit the rear end of the door 2 to occupy the position indicated in full lines in Fig. 2. The stop 25 may be depressed by the trip 30 23 coming in contact with a stop 26 which may be located at any convenient point. The stop 26 is adapted to be placed in the path of the trip 23 and the latter is beveled so as to ride on the stop 26 and depress the 35 stop 25. As indicated most clearly in Fig. 2 the stop 25 is of U shape so as to embrace the front and rear edges and the lower side of the transverse bar 20.

Figs. 2 and 4 indicate the trip 23 mounted 40 on the scraper so as to move therewith. The stop 26 is located in the drift or passage and is disposed a short distance in the rear of the material to be taken up by the scraper. While the scraper is traveling from the 45 point of discharge to the point of loading, the rear portion of the door 2 is held elevated so as not to dig into the bottom or floor of the passage. However, when the scraper reaches the point of loading, the trip 23 engages and rides beneath the stop 50 26, thereby permitting the rear portion of the door 2 to drop so as to pass beneath the load. The stop 26 is of a length to hold the trip 23 depressed until the door 2 is sufficiently loaded to prevent its rising by the 55 action of the spring 24 tending to elevate the trip 23 after the same has cleared the stop 26. It is to be understood that the stop 26 may be advanced as the material is 60 moved by the scraper in the discharge there-

of. Obviously the length of the stop 26 may vary but will be such as to hold the trip 23 depressed until the door 2 has received a sufficient load to prevent its assuming the dotted line position, indicated in Fig. 2.

70

When the scraper is drawn rearwardly by means of the tail rope, or cable 15 the upper end of the arm 8 is moved rearwardly thereby lowering the door 2 into approximately horizontal position. As the scraper moves 75 rearwardly it passes through the loose material, the latter passing over the door 2 and between the side walls 1, thereby automatically loading the scraper. After the scraper has been drawn rearwardly a sufficient distance to insure its receiving a proper load, the pull on the tail rope 15 is released and the rope 27 is drawn upon to pull the scraper forward to the point of discharge. The initial pull on the rope or cable 27 rocks 80 the arm 8 and effects a closing of the door 2 which is moved into an upright position thereby confining the load. When the scraper has advanced to the loading road or point of discharge the load automatically 85 discharges by reason of the bottomless formation of the scraper. To prevent the scraper from riding upward upon the material the side walls 1 have inner extensions 90 28 at their lower edges which ride under the material and hold the scraper on the bottom of the drift or passage. It will be understood that the scraper is self loading and self discharging, the opening of the scraper being effected by the initial pull on the tail 95 rope and the closing of the scraper being effected by the initial pull on the forward drag rope or cable.

95

The foregoing description and the drawings have reference to what may be considered the preferred, or approved, form of my invention. It is to be understood that I may make such changes in construction and arrangement and combination of parts, materials, dimensions, et cetera, as may 100 prove expedient and fall within the scope of the appended claims.

105

Having thus fully described my invention, what I claim as new and desire to secure by Letters Patent is:

115

1. In a scraper of the character set forth, a body, a closure hinged at its lower end to the body, a pivoted operating member, connecting means between the operating member and closure, tail and pull ropes connected with the operating member, and a movable stop adapted to limit the rearward movement of the operating member to hold the closure properly elevated at its rear end when in lower position to prevent its digging into the bottom of the mine.

120

2. In a scraper of the character set forth, a body, a closure hinged at its lower end to the body, a pivoted operating member, connecting means between the operating member, 125

130

member and closure, tail and pull ropes connected with the operating member, and a movable stop adapted to limit the rearward movement of the operating member to hold
5 the closure properly elevated at its rear end when in lower position to prevent its digging into the bottom of the mine, and a stop disposed in the path of the movable stop

to automatically trip the same at a predetermined point.

In testimony whereof I affix my signature in presence of two witnesses.

HARRY McKEAN CONNER.
